UNITED STATES PATENT OFFICE.

JAMES F. KEMPER, OF HARRISONBURG, VIRGINIA.

PIANO-VIOLIN.

SPECIFICATION forming part of Letters Patent No. 247,924, dated October 4, 1881.

Application filed September 17, 1880. (No model.)

To all whom it may concern:

Be it known that I, JAMES FOLEY KEMPER, a citizen of the United States, residing at Harrisonburg, in the county of Rockingham and State of Virginia, have invented certain new and useful Improvements in Violin-Pianos; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to improvements in violin-pianos, or that class of instruments comprising the piano strings and action with attachment for producing sounds having the characteristics of the violin tones; and it consists 20 in applying a number of endless and upwardly-converging band-bows passed over revolving tension-pulleys to an ordinary piano in such manner that they pass between the strings of the piano without touching them, and a number of 25 operating-levers set in motion by means of the piano mechanism, whereby the band-bows are deflected from their normal positions and brought in contact with the strings, thus producing the sounds or note corresponding to the 30 depressed key.

In the accompanying drawings, Figure 1 is a perspective view of a part of a piano to which my violin mechanism is attached, the hammers not being shown in order to better expose the 35 violin mechanism to view. Fig. 2 is a detailed perspective view of two strings and their operating mechanism on a larger scale. Fig. 3 is a detailed view of an endless band-bow, its tension-rollers, and deflecting-fingers. Fig. 4 is a modified construction of my invention, shown in perspective. Fig. 5 is a detail view of the mechanism operating the band-bows. Fig. 6 is a detail view of a piano-key and its 40 damper and connections with the band-bow. Fig. 7 is a perspective view of a stop whereby the hammer mechanism of the piano may be rendered inoperative. Fig. 8 is a perspective view of another modified construction of my violin mechanism. Fig. 9 is an enlarged detail view of a piano-key with my violin mechanism. Fig. 10 is a modification of the same.

Similar letters refer to similar parts throughout the several views.

A represents an ordinary key-board of a piano; B, the strings; a, piano-keys, and b tuning-pins. In practice an ordinary sound-board will be employed.

The keys a move on ordinary fulcrums, a', and are at the rear provided with fulcrum-stands a², which, by means of fulcrum-pins c, 55 support each a lever, C. The front ends of these levers C are suitably pivoted to a transverse bar, c', fastened to the key-board, and the rear ends of said levers are provided with anti-friction rollers c², which extend nearly to 60 the bridge b'. Below the bridge b' a number of pulleys, D, are hung between the rear part of the piano and a suitable bearing-bar, d, and above said bridge an elevated double bearing-bar, d', is attached in a suitable manner to the 70 frame of the instrument. This bar supports a number of comparatively small tension-rollers, E, by means of suitable spring-bearings, e, vertically above the pulleys D. Each pair of tension-rollers is provided with an endless band-bow, e', of a material qualified to do the same 75 service as the hand-bow of a violin. It will be seen that the rollers E are of less diameter than the lower rollers, D, so that the opposite sides of the endless band-bow e' converge upwardly toward each other. The inclined sides of these band-bows pass between the strings B, so that there is one string at each outer side of the band-bow and in close proximity to the same, but not close enough to be sounded when 85 the band-bow is in its normal position. The ends of the lever C are located on the inner sides of the band-bow in such manner that when the levers are raised by depressing the keys a they will strike and deflect the band-bow toward the string near by, and thus produce the sound of a violin or violoncello.

The pulleys D are provided with cranks d², which are coupled by a horizontal crank-bar, d³, and to this crank-bar the connecting-rod f 95 of an ordinary treadle-motion is attached, so that by operating the treadle all the band-bows e' are revolved.

The crank-bar d³ may be operated by two connecting-rods, one at each end, and they will 100 then be connected with the arms of a rock-shaft on the under side of the instrument, which rock-

shaft is operated by a treadle or foot power. Other suitable devices may be adopted to secure a perfect and well operating connection between the crank-bar and a foot-power. In 5 ease the bridge b' is curved the crank-bar d^3 will be divided into several smaller crank-bars, each attached to a separate treadle or foot-power, or to a suitable coupling of one foot-power.

10 The crank-motion may be substituted by pulleys and a cord, as shown in Figs. 4, 5, and 6. Each pulley D is, outside the bar d , provided with a cord-pulley, d^4 , over which a cord, d^5 , is passed. This cord passes through the bottom 15 of the piano over a guide-pulley, d^6 , and over the driving-pulley g of a fly-wheel, G , of an ordinary foot-power.

Instead of levers C , other deflecting devices 20 may be used, one of which I have illustrated in Figs. 4 and 6. In this device I provide the damper-rods g^2 of the piano with suitable extensions, g' , which are provided with the deflecting-rollers c^2 , and the ends of which are located below the ends of the damper-levers I , 25 as seen in Fig. 6. The deflecting-rollers c^2 are in this construction above the strings B , which, however, does not affect or change the principle of my invention.

If a violin solo is desired of my instrument, 30 I use a check for making the piano-hammer mechanism inoperative. This check consists of a transverse rod, J , fastened to the arms j of a rock-shaft, j' , hung in front of the lifting-jacks a^3 of the piano. By means of an arm, j^2 , 35 and connecting-rod j^3 , in imitation of an organ-stop draw, the said check may be operated at the front of the piano. When the rod j^3 is pushed in the rod J holds the jacks a^3 away from the butts a^4 of the piano-hammers, as indicated in dotted lines in Fig. 6, and the hammers are inoperative, and when the rod j^3 is pulled out the jacks a^3 resume their normal position again and the hammers are again 40 operative.

45 In Figs. 8, 9, and 10 I have illustrated another modification of my violin and damper mechanisms, which is especially adapted for square pianos, in which the strings B run at an angle to the piano-keys. The band-bows will 50 be in that case to the left of the ends of the cor-

responding keys, and the damper-rods, which must be placed between the inner sides of each band-bow, will have to be connected by jointed double levers K , as in Figs. 8 and 9, or by back shafts, L , as in Fig. 10. In Fig. 8 I have also 55 shown how I can connect a damper-block, M , directly to the extension g' of the damper-rod g^2 .

In practice I will subdivide my violin mechanism and piano mechanism in sections, which can be separately made operative or inoperative 60 by means of connecting or disconnecting stops, so that violin solos and piano accompaniments, or vice versa, may be played at any section of the key-board at pleasure.

It is obvious that when the treadles are not 65 operated the violin-bows will be stationary and the piano mechanism alone will be operative.

I claim as my invention and desire to secure by Letters Patent—

1. The combination, with the keys a , provided with the fulcrum-stands a^2 , and levers C , pivoted to the transverse bar c' , and provided with rollers c^2 , of the endless converging band-bows c' and strings B , substantially as described, and for the purpose set forth. 75

2. The combination, with the keys a , fulcrum-stands a^2 , levers C , having rollers c^2 , endless converging band-bows c' , and strings B , of the pulleys D , provided with cranks d^2 , crank-bar d^3 , and rod f , connecting the crank-bar with a 80 treadle, substantially as described, and for the purpose set forth.

3. The combination, with the rock-shaft j' , arms j , pivoted thereto and carrying the rod T , and arm j^2 , provided with connecting-rod j^3 , of 85 the keys a , lifting-jacks a^3 , and butts a^4 of the piano-hammers, substantially as described, and for the purpose set forth.

4. The combination, with the keys a , provided with damper-rods g^2 , having bent extensions g' , and deflecting-rollers c^2 , of the endless converging band-bows c' and damper-levers I , substantially as described, and for the purpose set forth. 90

In testimony whereof I affix my signature in 95 presence of two witnesses.

JAMES F. KEMPER.
